UNITED STATES PATENT OFFICE.

JOSEPH H. STANNARD, SR., OF COLUMBIA, SOUTH CAROLINA.

STEAM LOCOMOTIVE.

Application filed July 10, 1920. Serial No. 395,198.

To all whom it may concern:

Be it known that I, JOSEPH H. STANNARD, Sr., a citizen of the United States, residing at Columbia, in the county of Richland and 5 State of South Carolina, have invented new and useful Improvements in Steam Locomotives, of which the following is a specification.

The present invention relates to improvements in steam locomotives and particularly 10 to locomotives of that type employing superheaters.

With locomotives of this type it is of great importance that the flow of gases 15 through the flues into which the tubes of the superheater extend be cut off when steam is not circulating through said tubes. One of the objects of the present invention is to provide a simple means by which the damper 20 controlling the flow of gases through the superheater flues will be automatically controlled in unison with movement of the main throttle of the locomotive. More particularly, the invention provides means of 25 this character in which the parts that are likely to become worn or need replacement are all located outside of the locomotive where they will be readily accessible. That is, the invention provides means which may, 30 if necessary, be readily repaired or replaced so that a minimum amount of time is required for such work.

A further object of the invention is to provide a simple means for supplying a relatively 35 small amount of steam to the steam chests of the locomotive when the main throttle is closed, or practically closed, and the locomotive is drifting. The advantages of such a device are well known and this 40 feature of the invention relates primarily to providing a simple control means which is so connected with the superheater damper devices that both the drifting steam supply and the damper referred to, will be directly 45 controlled by the throttle actuating rod or member which is moved by the engineer.

In the accompanying drawings:—

Figure 1 is an elevation of a portion of a locomotive having an embodiment of the 50 present invention applied thereto;

Figure 2 is a detail view substantially on the line 2—2 of Figure 1;

Figure 3 is a vertical section through the front end of the locomotive, on an enlarged 55 scale;

Figure 4 is a sectional view substantially on the line 4—4 of Figure 3, several of the parts being omitted;

Figure 5 is a longitudinal section through the valve controlling the flue damper; 60

Figure 6 is a similar section of the drifting valve.

Referring to the drawings, 10 designates the front flue sheet of the boiler through which open the fire tubes 11 and the superheater flues 12. As usual the latter are shown arranged in the upper portion of the boiler and the superheater tubes 13 projecting therefrom are connected with a suitable header 14 from which the steam is conducted 70 to the valve chests of the locomotive cylinders in the ordinary manner.

As the invention hereinafter described and claimed is adapted for use with locomotive boilers of various types, it is not thought 75 necessary to describe or illustrate more in detail many of the features of such an apparatus.

Within the front end of the locomotive, about the usual exhaust nozzle 15 therein, is 80 arranged a flat table 16 and from the rear end of this table a baffle 17 extends to the top sheet of the smoke box. The table 16 is situated in a horizontal plane slightly below the lowest superheater flue 12 and the bottom 85 of the space formed between the forward flue sheet and said baffle 17 is closed by means including a vertically swinging damper 18. This damper is hinged at its rear end to a plate 19 that extends forward from the flue 90 sheet 10 and a weighted arm 20 acts to hold the damper in substantially horizontal position with its forward edge slightly in rear of the front of the baffle 17. Means are provided whereby when the throttle of the locomotive is open and steam is circulating through the superheater tubes 13, the damper 95 18 will be swung downward and rearward so that the gases and products of combustion can circulate freely through the superheater flues 12. Such means include a pressure cylinder 21 which is provided with a steam supply pipe 22 that extends outside the side wall of the locomotive shell or casing rearwardly and upwardly to a valve casing 23 100 supported on the top of the locomotive and which will be hereinafter more particularly referred to. A rock shaft 24 journaled in suitable bearings connected with the cylinder 21 is adapted to be rocked in one direction 105

110

when steam is admitted to said cylinder through the pipe 22 and in the opposite direction by the weighted lever 20 when the supply of steam is cut off. As shown, two arms 25, 26, are connected to said shaft, the latter being connected by a link 27 with the weight supporting arm 20 and the arm 25 is connected by a link 28 with an arm 29 on a rock shaft 30 that is mounted in suitable 10 bearings on the top of the table 16.

The vertical baffle 17 is perforated throughout its area in alinement with the superheater tubes 12, and on the forward face thereof are arranged a series of swinging plates or shutters 35 which are movable to and from a position where they will extend over and close said perforations. As shown, each of said plates is pivotally connected at its ends to uprights 31 secured to 15 the baffle 17 and at its opposite edge each of said plates is pivotally connected to a link 32, the lower end of which is connected by a short link 33 to an arm 34 on the inner end of the rock shaft 30.

From the foregoing description and the drawings, it will be seen that when steam is admitted to the cylinder 21 the damper 18 will be rocked downward and rearward and the plates 35 in advance of the baffle 17 20 swung upwardly about their pivotal axes into the positions shown in Figure 3, whereby there will be free an unobstructive draft through the superheater flues 12. When, however, the main throttle of the locomotive 25 is closed so that steam no longer circulates through the superheater tubes, the weighted arm 20 will act to swing the damper 18 upward, closing the passage between the forward flue sheet and the baffle 17; and the 30 swinging plates 35 in front of the baffle will be moved so as to completely close the perforations in such plate.

The supply of steam to the pressure cylinder 21 through the conduit 22 is controlled 45 by a three-way valve mounted in the casing 23. Steam from a suitable chamber within the boiler is admitted to the valve casing 23 through a pipe 40 and said casing communicates with the pipe or conduit 22 and also 50 with an exhaust pipe 41. The valve in the casing 23 is provided at its end with an arm 42 which is connected through a link 43 with a lever 44 fulcrumed on the locomotive. At its lower end this lever 44 has a notch which 55 engages a lug or lateral projection on the reciprocating rod 45 which is moved by the engineer for opening and closing the main throttle of the locomotive. Therefore, when the rod 45 is moved to open the locomotive 60 throttle, the valve in the casing 23 will be turned to establish communication between the conduit or pipe 22 and the inlet pipe 40. Thus steam will be supplied to the pressure cylinder 21 and the damper 18 will be opened 65 and the perforations in the baffle 17 uncov-

ered so that the maximum amount of draft through the superheater flues will be permitted. When, however, the rod 45 is shifted to close the throttle the valve in casing 23 will be turned so that the pipe or conduit 22 70 will be brought into communication with the exhaust pipe 41 and cut off from the inlet pipe 40. Under these conditions, the pressure in the cylinder 21 will be exhausted and the weighted arm 20 will instantly act to 75 move the damper 18 to closed position and to swing the hinged plates downward against the baffle 17, closing the perforations therethrough.

It will be seen that with such a construction and arrangement, it is impossible for any steam, that might leak past the throttle or the valve in the casing 23 to create such a pressure in the cylinder 21 as to open the damper when the locomotive is standing 80 still, for example. It means generally similar to those herein described that have been heretofore proposed, it has frequently occurred that when the main throttle was presumably closed, steam would gain access to 90 the cylinder 21 and after a sufficient interval of time effect an opening of the damper which would permit flow of combustible gases through the superheater flues when no steam was circulating in the superheater 95 and, therefore, cause injury to the superheater tubes.

The invention also includes means whereby when the main throttle has been closed, and the locomotive is drifting, a relatively small amount of steam will be supplied to the valve chests of the locomotive cylinders so that the action of the pistons will not operate to draw into such cylinders particles from the front end of the locomotive. 100 As shown, this means includes a pipe or conduit 50, which leads from a valve casing 51 that is mounted on the same support as the valve casing 23 on top of the locomotive, said pipe having a branch leading to each 105 of the steam chests 52. A non-return valve 53 is provided in each branch of the pipe 50 and steam is supplied to the casing 51 through a supply pipe 54 corresponding to the pipe 40 of the valve casing 23. The 110 valves in the casings 23 and 51 are connected by a coupling sleeve 55, so that movement of the throttle actuating rod 45 will be communicated to the valves in both said casings. The valve in the casing 51 is a 115 two-way valve controlling merely an inlet and outlet port. When these ports are connected steam is supplied through the pipe 50 to the valve chests 52 in sufficient quantity to prevent grit and products of combustion being drawn back from the stack onto the valve seat by the suction of the piston in the cylinder and also to prevent 120 the carbonization of the lubricant which is supplied to the valve chests. 125

In practice the throttle control lever in the cab will be moved slightly past the position in which the throttle is closed in establishing communication between the boiler 5 and the pipes 50, this being permitted by the usual "lost motion" connections between said lever and throttle.

When the locomotive comes to a complete stop the throttle lever may be reversely 10 shifted sufficiently to cut off the flow of steam through the pipes 50 without moving the main throttle from its seat.

A suitable cock connected to an actuating rod 54, extending to the cab of the locomotive, may be provided in the steam supply 15 pipe 54 so that the engineer may completely cut off the supply of steam to the casing 51 when desired.

The slight movement of the valve in casing 51 in cutting off flow of steam to the pipes 50 when the locomotive has come to rest need not be sufficient to destroy the connection between the conduit 22 and exhaust pipe 41.

It will be seen that the invention provides a very simple means which is actuated from the engineer's throttle control lever whereby the superheater flue damper will be maintained in proper relation to said flues 25 according as the circulation of steam through the superheater tubes is controlled and that when said damper is in closed position, the cylinder 21 and its actuating means is in constant communication with the 30 atmosphere so that accidental swinging of the damper to open position is impossible.

All of the parts controlling the supply of steam to the cylinder 21 and to the locomotive valve chests while the locomotive is 35 drifting are arranged exteriorly of the locomotive and in a position where they can be readily inspected and repaired if necessary. The two valves being connected are simultaneously moved whenever the throttle actuating 40 lever is shifted by the engineer.

Having thus described the invention what is claimed is:

1. The combination of a steam locomotive boiler including a front flue sheet, superheater flues opening through said flue sheet, a perforated baffle in advance of the forward ends of the superheater flues, a damper adapted to close the lower end of the space between the front flue sheet and said baffle, a plurality of plates pivotally supported in front of the baffle and movable to and from a position to close the perforations thereof, means acting to maintain the damper closed and said plates across the perforations in the baffle, means for opening the damper and moving said plates to uncover the perforations in the baffle including a pressure cylinder and a conduit for conducting steam thereto from the boiler, a valve controlling flow through said conduit, 55 and means connecting said valve with the locomotive throttle, whereby when the throttle is opened steam will be supplied to the cylinder to open the damper and uncover the perforations in the baffle and when the throttle is closed said cylinder will be in communication with an exhaust port.
2. In a steam locomotive the combination with a boiler including a front flue sheet, and superheater flues, opening 75 through said flue sheets, of a perforated baffle extending across the front ends of said flues, a pivotally mounted damper adapted to close the lower end of the space between said baffle and the front flue sheet, 80 a plurality of shutter plates each hinged at one edge to the front face of the baffle, a draft link pivotally connected with all of said plates adjacent their opposite edges, whereby said plates may be simultaneously 85 adjusted to extend forward from the baffle or downwardly over the perforations therein, a pressure cylinder, a conduit for supplying steam from the boiler to said cylinder, a shaft adapted to be rocked when steam is admitted to said cylinder, and connected to both the damper and said draft link, whereby when steam is admitted to the cylinder the damper will be opened and said plates adjusted to uncover the perforations in the baffle, and means for automatically closing the damper and moving said plates across the perforations in the baffle when the supply of steam to the cylinder is cut off.
3. The combination in a steam locomotive provided with superheater flues, of a damper for controlling the flow of gases through said flues, means normally holding said damper closed, means for opening 95 said damper including a pressure cylinder and a conduit for supplying steam thereto, a valve controlling flow through said conduit, a conduit for supplying steam from the boiler to a steam chest of the locomotive 100 when the locomotive is drifting, a valve controlling flow through the last said conduit, means connecting said valves, and a connection between one of said valves and the locomotive throttle actuating devices, 105 whereby both said valves will be positively operated as the throttle is closed and opened.
4. The combination of a steam locomotive boiler including a front flue sheet, superheater tubes opening through said sheet, a perforated baffle in advance of the forward ends of the superheater tubes, a damper adapted to close the lower end of the space between the front flue sheet and said baffle, a plurality of plates pivotally supported at one edge adjacent the baffle, a bar pivotally connected with each of said plates, a rock shaft having an arm connected to said bar, a pressure cylinder, a 115

- shaft adapted to be rocked in one direction when steam is admitted to said cylinder and provided with two arms, means connecting one of said arms with the damper, means connecting the other of said arms with the actuating rock shaft of said pivotally mounted plates whereby, when steam is supplied to the cylinder, the damper will be adjusted to close the lower end of the space 10 between the flue sheet and baffle and the pivotally mounted plates turned to close the perforations in the baffles, means for supplying steam to the cylinder, and means for moving the damper and pivoted plates to 15 open position when the supply of steam to the cylinder is cut off.
5. The combination in a steam locomotive provided with superheater flues, of a damper controlling the flow of gases 20 through said flues, means acting to hold the damper in closed position, means for opening the damper comprising a pressure cylinder and a conduit for supplying steam thereto, a valve controlling the flow of steam 25 through said conduit means for supplying steam to the locomotive cylinders when the engine is drifting, including a valve arranged adjacent said damper controlling valve, means connecting said valves for effecting simultaneous movement thereof, 30 means for actuating the throttle valve of a locomotive, connections between said means and the said valves whereby, when the throttle is closed, the valves will be positively actuated to close the damper and supply steam to the locomotive cylinders, and when the throttle is opened the supply of steam to the damper controlling devices will be positively cut off, and an independent valve adapted to cut off the supply of steam to the conduit to which steam is supplied to the locomotive cylinders when the locomotive is drifting.

by the latter will be positively moved as said rod is reciprocated.

35

6. The combination in a steam locomotive provided with superheater flues, of a damper controlling the flow of gases through said flues, means acting to hold the damper in closed position, means for opening the damper comprising a pressure cylinder and a conduit for supplying steam thereto, a valve controlling the flow of steam through said conduit, means for supplying steam to the locomotive cylinders when the engine is drifting, including a valve arranged adjacent said damper controlling valve, means connecting said valves for effecting simultaneous movement thereof, means for actuating the throttle valve of a locomotive, connections between said means and the said valves whereby, when the throttle is closed, the valves will be positively actuated to close the damper and supply steam to the locomotive cylinders, and when the throttle is opened the supply of steam to the damper controlling devices will be positively cut off, and an independent valve adapted to cut off the supply of steam to the conduit to which steam is supplied to the locomotive cylinders when the locomotive is drifting.
